UNITED STATES PATENT OFFICE.

DUDLEY FREEMAN, OF ROXBURY, MASSACHUSETTS, ASSIGNOR TO PANTHER RUBBER MANUFACTURING COMPANY, OF STOUGHTON, MASSACHUSETTS, A CORPORATION OF MASSACHUSETTS.

DESIGN FOR A SHOE SOLE.

● 60,229.

Specification for Design.

Patented Jan. 17, 1922.

Application filed September 27, 1921. Serial No. 503,624. Term of patent 7 years.

To all whom it may concern:

Be it known that I, DUDLEY FREEMAN, a citizen of the United States, residing at Roxbury, in the county of Suffolk and Commonwealth of Massachusetts, have invented a new, original, and ornamental Design for a Shoe Sole, of which the following is a specification, reference being had to the

accompanying drawing, forming a part thereof.

The figure of the drawing is a plan view of a shoe sole incorporating my new design.

I claim:

The ornamental design for a shoe sole as shown.

DUDLEY FREEMAN.
